C. E. HOLT,
FRAME ADJUSTER.
APPLICATION FILED FEB. 11, 1919.

1,358,210.

Patented Nov. 9, 1920.

Clarence E. Holt, Inventor

P. Kume Talbert Attorney

UNITED STATES PATENT OFFICE.

CLARENCE ERNEST HOLT, OF HENRYETTA, OKLAHOMA.

FRAME-ADJUSTER.

1,358,210.

Specification of Letters Patent.

Patented Nov. 9, 1920.

Application filed February 11, 1919. Serial No. 276,415.

To all whom it may concern:

Be it known that I, CLARENCE E. HOLT, a citizen of the United States of America, residing at Henryetta, in the county of Okmulgee and State of Oklahoma, have invented new and useful Improvements in Frame-Adjusters of which the following is a specification.

The object of the invention is principally to provide a mechanism for use in conjunction with a cultivator of the toothed-drum variety, so that the said drum may be readily and quickly elevated to free it from the ground or just as quickly lowered to bring it in operative contact with the ground. The cultivator with which the improved attachment is designed for use is that shown in the applicant's Patent No. 1,289,176, dated Dec. 31, 1918. The improved mechanism is provided with a latch-control lever positioned adjacent the cultivator seat and this lever is operatively connected with two stub axles on which the cultivator wheels are journaled. Thus the operation of the lever lowers the cultivating drum until the latter contacts with the ground and thereafter raises the wheels to free them from the ground. It may also be manipulated to effect the reverse of these operations and further it may be adjusted to regulate the depth to which the teeth of the drum penetrate the ground.

As illustrated and described, a specific embodiment of the invention is adhered to but to this embodiment it is not to be restricted. Actual practical use may suggest certain desirable changes or alterations and the right is claimed to make any falling within the scope of the subjoined claim.

In the accompanying drawings forming part of this application and in which the same numerals of reference designate the same parts:

Figure 1 is a side elevation of the cultivator showing the wheel-elevating mechanism attached thereto.

Fig. 2 is a perspective view of the mechanism *per se*.

Fig. 3 is an enlarged sectional view on line 3-3 of Fig. 2.

As shown, the invention is applied to the cultivator generally designated A, this cul-

in which the drum 1 is carried, the drum being of the usual character and provided with soil-engaging teeth, as is shown. The U-shape frame is formed with the two legs 2 and with the transverse member 3 at the center of which the seat 4 is carried. The legs 2 are, as is shown, channel shape in cross-section, each leg being provided with longitudinal side flanges 5 and 6 which are undercut so that the plates 7 may be carried by the legs for longitudinal or vertical movement there along, the edges of the plate lying behind the undercut portions of the flanges. Each plate 7 adjacent its lower end carries a stub axle 8 which is attached to it by appropriate bolts or cap screws 9, and on these stub axles the wheels 10 are rotatably mounted. Directly above the stub axle there are pinions 11, these pinions being positioned adjacent the upper ends of the plates and each pinion being rotatably mounted on a stub 12 carried by its attendant plate.

The flange 5 of each leg 2 between certain points in its length is provided with rack teeth 13 with which the teeth of the pinion 11 mesh. While the flange 6 on the inner end of that portion which overlies the plate 7 is provided with a T-slot in which a longitudinally T-shaped rib 14 slidably engages. This rib being formed on the back edge of a rail 15 is provided with rack teeth 16 also meshing with the teeth of the pinion 11.

The upper ends of the legs 2 are extended above the transverse member 3 and these extending ends are each provided with a bearing in which the rock shaft 17 is journaled, the latter being positioned above the transverse member 3 and extending across the frame beneath the seat 4. That this shaft may be rocked by the operator or driver of the machine and secured in any position to which it may be rocked, there is provided a tooth segment 18 which is mounted on the transverse member 3 beside the seat 4 and this segment is formed with a bearing for the shaft 17 at the center of the rack. Fixed to the shelf 18 beside the segment, there is a hand-lever 19 and this hand-lever carries a manually operated spring latch 20 which is engageable with any one of the teeth of the segment so that the lever may be moved

forwardly and rearwardly and locked in any position to which it may be moved thus making it possible to rock the shaft and also lock it in any position to which it may be moved, since the lever is secured to the shaft.

The shaft 3 protrudes from its bearings a sufficient distance to permit the attachment on each end of a segmental gear 21, 10 these two segmental gears measuring with the teeth of the rails 15 on either side of the frame. It is thus apparent that rocking movement imparted to the shaft will result in longitudinal movement up or down being 15 imparted to the rails 15, with the result that the pinions 11 are rotated on their stubs. Such rotation of the pinions will obviously affect the raising or lowering of the plates 7, since the pinions mesh with the teeth 13 20 formed on the flange 6. Thus as the lever 20 is moved rearwardly or forwardly the plates 7 are raised or lowered with the consequent raising or lowering of the wheels 10, thereby causing the drum to be lowered to 25 the ground leaving the wheels elevated or causing the wheels to be moved to the ground with the consequent elevation of the drum if the latter be upon the ground. Obviously the position of the plates may be 30 regulated and thus the positions of the

wheels regulated so that the teeth of the drum may be adjusted to penetrate the ground to any depth desired.

The invention having been described what is claimed as new and useful is:

The combination with a cultivator having an inverted U-shaped frame and a cultivating drum journaled in the legs of said frame, of wheels carried by the legs of said frame, the legs of the frame being channel 40 shaped and formed with undercut flanges, plates slidably mounted on the frame behind said flanges, stub axles mounted on the plates and carrying the cultivator wheels, pinions rotatably mounted on said plates, 45 one flange of each leg being formed with rack teeth, the pinions meshing with the teeth on the two flanges, a rail slidably mounted in the other flange of each leg, said rails being formed with teeth and meshing 50 with the pinions, a transversely disposed shaft journaled in the said legs, segment gears mounted on the shaft and meshing with the rails, and a latch control manually operable lever connected with the shaft 55 whereby the latter may be rocked for the useful purpose herein specified.

In testimony whereof I affix my signature.

CLARENCE ERNEST HOLT.
